UNITED STATES PATENT OFFICE.

EMANUEL FITZ, OF ASTORIA, ILLINOIS.

ADJUSTABLE GAGE AND MARKER.

1,110,763.

Specification of Letters Patent. Patented Sept. 15, 1914.

Application filed September 22, 1913. Serial No. 791,192.

To all whom it may concern:

Be it known that I, EMANUEL FITZ, a citizen of the United States, residing at Astoria, in the county of Fulton and State of Illinois, have invented certain new and useful Improvements in Adjustable Gages and Markers, of which the following is a specification, reference being had to the accompanying drawings.

10 This invention relates to improvements in gages and it more particularly relates to certain improvements in a form of adjustable gage and marker, such as described and illustrated in my Patent Number 1,066,592.

15 One of the objects of this invention is to provide an improved and easily operated means for alternately holding and releasing the handle and allowing it to be swung into folded position.

20 Another object of the invention is to provide an improved form of cutting or marking members and to generally improve devices of this character without materially increasing the cost of manufacture.

25 In the accompanying drawings which supplement this specification, Figure 1 is an elevation view of my gage and marker in its operative position on a clapboard. Fig. 2 is an enlarged longitudinal sectional view on the line 2—2, Fig. 1; and Fig. 3 is an enlarged end elevation view.

30 In these drawings in which similar reference characters correspond with similar parts throughout the several views, the main body or frame of the device comprises an elongated bar 5 consisting of two apertured flanges 6 and 7, respectively, which extend at right angles, to each other. The flange 6 is provided with a segmental extension 8 at 35 its medial portion having its arcuate edge provided with a series of notches 9. The flange 7 carries a series of cutter disks 10, rotatably mounted upon the screws 11, washers 12 being disposed between the respective disks and the heads of the screws 11. Each end of the flange 7 is turned at right angles to the major portion thereof, as at 13, and on each right-angled extension or flange 13 is secured a gage arm 14 by 40 means of screws 15. The upper end of the arm 14 is slotted transversely, and one of the screws 15 extends through the slot and engages with the flange 13, so as to allow for limited lateral adjustment of the arm 14 on 45 the flange 13.

The handle member 16 is pivotally connected to the extension 8 by means of the screw 17 and carried by the handle member and arranged upon the end face thereof is a spring 19, one end of which is rigidly secured to the handle at 20, while the other end thereof is removably engaged with the notches 9 to yieldably retain the handle member in various adjusted positions. The handle 16 is provided with an opening 21 through which the pin 22 is adapted to extend so that the spring member may be readily released by pressing upon the pin from the upper face of the handle. The pin 22 is carried by the spring 19 and suitably connected thereto as shown at 23. The free end of the handle 16' is offset from the major portion of the handle, the lower plane surface thereof being substantially parallel with the medial portion thereof, and lying 75 in a plane coinciding with the cutting edges of the disk 10.

In the operation of the device, the plane surface 16' rests upon the surface of the clapboards to be gaged and marked, while 80 the arms 14 rest against the vertical corner strip or other member against which the clapboards are to be fitted. The handle 16 is then manipulated for imparting a slight longitudinal movement to the bar 5, so as to cause the disks 10 to cut into the surface of the clapboard and mark it at the proper place to be sawed off and fitted against the upright member. When it is desired to 85 change the angle of the members 5 and 16, with relation to one another, it is only necessary to push downward against the button or stud 22, for releasing the engagement of the elements 8 and 19, whereupon the device 90 may be folded or adjusted, in an obvious 95 manner.

It will be seen that I have provided an improved gage and marker of this character which is fully capable of attaining the desired objects, as specified in the foregoing, 100 in a thoroughly practical and desirable manner.

While I have illustrated what I believe to be the preferred embodiment of my invention, it is to be understood that the invention is not limited thereto, but various changes in form, proportion and arrangement of parts may be made without departing from the principle of the invention, as defined in the appended claims.

Having thus described this invention, what I claim is:—

1. A combined gage and marker comprising a bar consisting of flanges extending at right angles to one another, one of said flanges having a series of cutter disks pivotally mounted thereon, a pair of gage arms mounted on said bar, and a handle pivotally and adjustably mounted on the other of said flanges and extending at right angles to the flange having the cutter disks thereon.
2. A combined gage and marker comprising a bar consisting of two flanges extending at right angles to one another, a series of

cutter disks pivotally mounted on one of the flanges, a handle mounted on the other flange and extending at an angle to the flange having the cutter disks thereon, and a gage arm carried on each end of the flanged bar, said handle having an offset lower surface extending in a plane parallel with the major portion of the handle and coinciding with the cutter edges of the disks.

In testimony whereof I hereunto affix my signature in the presence of two witnesses.

EMANUEL FITZ.
